UNITED STATES PATENT OFFICE

90,741

DESIGN FOR A PORTABLE ELECTRIC HEATER

Willard O. Twombly, Jackson, Mich., assignor to
C T Electric Company, Jackson, Mich., a cor-
poration of Michigan

Application January 7, 1933. Serial No. 46,757

Term of patent 14 years

To all whom it may concern:

Be it known that I, WILLARD O. TWOMBLY, a citizen of the United States, residing at Jackson, in the county of Jackson and State of Michigan, have invented a new, original, and ornamental

Design for Portable Electric Heaters, of which the following is a specification, reference being had to the accompanying drawing, forming part thereof.

The figure is a perspective view of a portable electric heater showing my new design.

The invention resides in an ornamental design for portable electric heaters having as its dominant features a flat top and a base spaced by a plurality of vertically disposed channel reflectors constituting a cylindrical body.

I claim:

The ornamental design for a portable electric heater substantially as shown and described.
